UNITED STATES PATENT OFFICE.

RICHARD B. HALL, OF FAIRTON, NEW JERSEY.

SHINGLE FOR REPAIRING OLD OR LEAKY ROOFS.

1,090,531.

Specification of Letters Patent. Patented Mar. 17, 1914.

Application filed October 22, 1913. Serial No. 796,603.

To all whom it may concern:

Be it known that I, RICHARD B. HALL, citizen of the United States, residing at Fairton, in the county of Cumberland and State of New Jersey, have invented certain new and useful Improvements in Shingles for Repairing Old or Leaky Roofs, of which the following is a specification.

The present invention relates to a sheet metal shingle which is especially designed for repairing old and leaky roofs, the primary object of the invention being to provide a shingle of this character which embodies novel features of construction whereby it can be readily applied to decayed or broken wooden shingles in such a manner as to repair the roof and stop leaks therein without the necessity of removing and replacing the broken or decayed wooden shingle.

A further object of the invention is to provide a shingle of this character which is comparatively simple and inexpensive in its construction, which can be readily applied to a roof, either to leaky portions thereof or to the entire roof, and which will fit over worn and defective wooden shingles in such a manner as to effectively repair the roof and stop all leaks therein.

With these and other objects in view, the invention consists in certain novel combinations and arrangements of the parts as will more fully appear as the description proceeds, the novel features thereof being pointed out in the appended claim.

For a full understanding of the invention, reference is to be had to the following description and accompanying drawing, in which:

Figure 1 is a vertical sectional view through a portion of an old shingle roof having the sheet metal shingle applied thereto. Fig. 2 is a transverse sectional view on the line 2—2 of Fig. 1. Fig. 3 is a plan view of a sheet of the shingles. Fig. 4 is a front view of the same. Fig. 5 is a plan view of a sheet of the shingles having a slightly different arrangement. Fig. 6 is a transverse sectional view through one of the ridge members. Fig. 7 is a longitudinal sectional view through one of the shingles, and Fig. 8 is a similar view showing a slight modification.

Corresponding and like parts are referred to in the following description and indi-

cated in all the views of the drawing by the same reference characters.

Referring to the drawings, the numeral 1 designates an inclined roof surface which is provided upon the exterior thereof with wooden shingles 2, the said shingles being applied in the ordinary manner. These wooden shingles overlap a sufficient amount to prevent leakage when the shingles are in good condition, although wooden shingles are subject to decay, and under the action of heat and rain not infrequently curl and crack so as to cause leaks in the roof. The ordinary manner of repairing a leaky shingle roof is to remove the broken or decayed shingles and replace the same with new shingles, although this is attended with difficulties, owing to the large amount of overlap between successive rows of the shingles.

In order to overcome the above difficulty in repairing leaky shingle roofs, the sheet metal shingle 3 has been devised. This sheet metal shingle is formed in sheets or plates such as indicated at A by Fig. 3 and at B by Fig. 5. These plates are all of a sufficient length to fit over the projecting ends of a number of wooden shingles, and have a width slightly greater than the exposed portion of the shingles so as to provide a slight overlap of the metal shingles when the latter are applied. The sheets or plates A and B are provided with the grooves or depressions 4 which correspond to the spaces between adjacent shingles and subdivide the sheet or plate into a plurality of individual shingle elements adapted to fit over the shingles of the roof. These grooves or depressions 4 not only serve to retain the wooden shingles against turning or twisting and to secure a firm seating of the metal shingle upon the wooden shingles, but also gives the finished roof the appearance of a shingle roof, so that a roof may be repaired in spots or sections without destroying the appearance of the entire roof. It will also be observed that the forward edge of the sheet A is formed with a downwardly projecting flange 5 which fits over the ends or extremities of the wooden shingles. In this connection attention is directed to the modification shown by Fig. 8, in which this flange 5 is shown as provided at the lower edge thereof with a returned lip 6 which extends under the end of the shingle so as to securely lock the metal shingle with the

wooden shingle and eliminate any danger of the metal shingle being raised or displaced by a heavy wind.

The sheet or plate B is similar to the plate A, with the exception that the grooves or depressions 4 are arranged in a slightly different manner, a half shingle section 3^b being provided at the end of the sheet or plate B, while the plate A begins with a full shingle section.

In applying the metal shingles to an old shingle roof, the plates A and B are used alternately upon the successive rows of shingles, the grooves or depressions 4 of the plates B being disposed at intermediate points between the grooves 4 of the plates A, in the same manner in which the shingles upon successive rows are arranged to cover the joints between underlying shingles. Suitable fastening members such as the nails 6^a may be employed for securing the metal shingles in position. In applying the shingles, the upper edge of the metal shingle is inserted under the ends of the next higher row of wooden shingles, and the nails 6^a then driven through the ends of the said next higher row of wooden shingles so as to penetrate the upper edge portion of the metal shingle and secure the metal shingle in position. The nails or fastening members 6^a are thus caused to engage the metal shingles at the unexposed portions thereof which are fitted under the projecting ends of the next higher row of shingles. The heads of the nails 6^a are covered by the metal shingles fitted over the next higher row of wooden shingles, so that both the nails and the openings through which the same pass are completely covered. The sheets or plates A are formed with full shingle sections at one end thereof, and with a narrow section 3^a at the opposite end, the said narrow section being adapted to be overlapped by the full shingle section at the end of the next plate A, thereby providing a continuous metal covering or sheeting for the row of shingles which is absolutely weather-tight. In a similar manner, the sheets B are provided at the inner ends thereof with the narrow shingle sections 3^c

corresponding to the before mentioned narrow sections 3^a and adapted to be overlapped by adjacent shingle sheets.

A special member, similar to that shown by Fig. 6, may be employed at the ridge of the roof, the said section comprising the two angularly disposed plates 3^a having a hollow wing 3^e at their junction which may receive the projecting ends of the upper row of shingles on one side of the ridge.

As previously stated, these metal shingles are primarily designed for use in repairing old or leaky shingle roofs, and they may either be applied to the entire roof, or only to certain spots or portions thereof which may be out of repair. The peculiar manner of forming the shingles causes them to closely resemble the wooden shingles when placed in position, so that to all appearances the roof is formed of the ordinary wooden shingles.

The essential feature of the improved sheet metal shingle is the construction of the same in the form of a hollow shell which can be fitted over decayed or broken shingles in such a manner as to repair the roof without the necessity of removing the old shingles, thereby enabling the roof to be repaired at less expense and much more quickly than is possible where it is necessary to remove the old shingles and replace the same with new shingles.

Having thus described the invention, what I claim as new and desire to secure by Letters Patent, is:

A sheet metal shingle for repairing leaky shingle roofs, the said sheet metal shingle being in the form of a hollow shell adapted to fit over the projecting ends of a series of shingles, the said shell being provided with grooves or depressions corresponding to and fitting between the joints between the wooden shingles being covered.

In testimony whereof I affix my signature in presence of two witnesses.

RICHARD B. HALL.
